Primary Examiner — Paula Greene(74) *Attorney, Agent, or Firm* — Sterne, Kessler, Goldstein & Fox P.L.C.(57) **CLAIM**

The ornamental design for an audio listening system, as shown and described.

DESCRIPTION

FIG. 1 is a perspective view of an earpiece of an audio listening system in accordance with one embodiment of the present invention;

FIG. 2 is a front view of the embodiment of an earpiece of an audio listening system depicted in FIG. 1;

FIG. 3 is rear view of the embodiment of an earpiece of an audio listening system depicted in FIG. 1

FIG. 4 is a right side view of the embodiment of an earpiece of an audio listening system depicted in FIG. 1;

FIG. 5 is a left side view of the embodiment of an earpiece of an audio listening system depicted in FIG. 1;

FIG. 6 is a top view of the embodiment of an earpiece of an audio listening system depicted in FIG. 1;

FIG. 7 is a bottom view of the embodiment of an earpiece of an audio listening system depicted in FIG. 1; and,

FIG. 8 is front view of an audio listening system with a pair of earpieces.

The broken lines in the figures show portions of the audio listening system that form no part of the claimed design.
